CLAIM

The ornamental design for an architectural panel, as shown and described.

DESCRIPTION

Portions of the disclosure of this patent document contain material to which claims for copyright are made. The copyright owner has no objection to the reproduction of the patent document or the patent disclosure, as it appears in the U.S. Patent Office records, but reserves all other copyright rights whatsoever.

FIG. 1 is a front perspective view of an architectural panel showing the new design, shown in a first embodiment;

FIG. 2 is a back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a front perspective view of the architectural panel, shown in a second embodiment. The second embodiment of the architectural panel includes a left-side view and a right-side view identical to the left-side view and the right-side view shown for the first embodiment;

FIG. 10 is a back perspective view thereof;

FIG. 11 is a front view thereof;

FIG. 12 is a back view thereof;

FIG. 13 is a top view thereof; and,

FIG. 14 is a bottom view thereof.

The broken lines depict portions of the architectural panel that form no part of the claimed design.
